UNITED STATES PATENT OFFICE.

RUMSEY W. SCOTT, OF NEW YORK, N. Y.

MOTOR-CONTROLLER.

SPECIFICATION forming part of Letters Patent No. 681,269, dated August 27, 1901.

Application filed December 19, 1900. Serial No. 40,349. (No model.)

To all whom it may concern:

Be it known that I, RUMSEY W. SCOTT, a citizen of the United States, residing at New York, State of New York, have invented certain new and useful Improvements in Motor-Controllers, of which the following is a clear, full, and exact description.

My invention relates to an electric-motor controller, and particularly to a controller for use with electric elevators; and my object is to produce a device which is simple, durable, efficient, and which will not easily get out of order.

Other subordinate advantages of my invention will be apparent from the accompanying drawings and description, which disclose one embodiment of the invention.

My invention will be defined in the claims.

In the preferred embodiment shown in the drawings, Figure 1 shows a side elevation of my controller in place on a slate board; Fig. 2, a diagram of connections, and Fig. 3 a detail of a car and the rack-actuating mechanism.

In the drawings, illustrating the preferred embodiment of my invention, I have shown my invention applied to an elevator mechanism.

1, Fig. 3, is a car traveling between suitable guideways 22 in the elevator-well and raised by an electric motor, preferably compound wound, whose windings are shown in diagram in Fig. 2. In order to regulate the supply of current to the armature of the motor when the same is started or reversed, I have provided a rheostat in the motor-circuit and a contact-piece also in said circuit, which passes over the rheostat to cut out the resistances thereof. I preferably also have a movable stop for the contact-piece, which is adapted to control the position of the contact-piece on the rheostat, and thus control the speed of the motor.

In the drawings the motor is shown in Fig. 2, in which 3 represents the armature-winding, 4 the series field-winding, and 5 the shunt field-coils.

7 is a suitable resistance, in this case a bank of incandescent lamps, short-circuited across the terminals of the shunt field-coils to take the kick of the shunt when it is opened. The rheostat preferably consists of a series of

resistances 88, between stationary terminal blocks 99, mounted on a suitable slate 10 and arranged in the arc of a circle. The lower end 55 of the rheostat is preferably connected to one main through the armature-circuit and the other main being connected to an arc-shaped contact-bar 11.

12 is the movable contact-piece, which may 60 be carried on and insulated from (see 12^a, Fig. 2) an arm 13, pivoted at the center 13^a of the arc of the terminals 99, and which closes the motor-circuit through the rheostat. As the contact-piece is moved forward over 65 the rheostat from the position shown in full lines in Fig. 1 it will cut resistances 88 out of the motor-circuit and increase the speed of the motor.

14 is a movable stop which holds the arm 70 13 from moving forward over the rheostat and controls the position of the contact-piece 12 on the rheostat. In the present embodiment I have connected the movable stop 14 with the car by a shipper-rope 15, Fig. 3, 75 passing through the car and over a wheel 16, carrying a toothed wheel 17, which meshes with a reciprocating rack 18. In order to cause the movable stop 14, and therefore the contact-piece 12, to move downward on a 80 movement of the shipper-rope and rack in either direction, I have provided a wheel 19, meshing with the rack and preferably carrying a crank-pin 20, which is connected to stop 14 by the link 21.

21^a is a bar sliding in a guideway 21^b and pivoted to link 21 by stop-pin 14 for guiding the movement of the stop 14. As the rack is moved in either direction from the position shown in full lines in Fig. 1 the stop 14 will 90 be moved downwardly and will cause the arm 13 and contact-piece 12 to move forward over the rheostat.

The shipper-rope and rack have preferably only a short movement, and in order that the 95 contact-piece 12 shall not cut out the resistances in the motor-circuit too quickly when the rope is pulled I have made the contact-piece adapted to automatically pass over the rheostat—that is, it is not positively connected with the shipper-rope, but moves independently of the same in the present embodiment by gravity. As the shipper-rope is quickly pulled the stop 14 will move away

from the arm 13, and the arm will start to fall and its motion is regulated by, preferably, a dash-pot 22. It makes no difference, therefore, how quickly the shipper-rope or 5 rack 18 is moved the arm 13 and contact-piece 12 will always move slowly, thus avoiding a sudden rush of current through the motor-armature. 23^a is a spring attached to bar 21^a and serving to counterbalance in part the 10 weight of the parts and also to tend to keep the parts normally in the position shown in Fig. 1.

In order to reverse the direction of current in the motor-circuit, I have provided a pivoted switch-arm 23, whose ends are insulated from each other, as seen at 24 in Fig. 2. These ends move into spring-jaws 25 28 and 29 32. To throw the switch, I prefer to use a pivoted cam 33, having arms 34 35, forming faces 36 37, making an angle with each other. Located between these cam-faces is a movable actuating part, preferably consisting of a roller-stud 38, connected with the shipper-rope by an arm 39, fixed to the rack 18. As the shipper-rope and rack are moved in one direction or the other the stud 38 will strike the cam-face 36 or 37 and rock the cam and throw the reversing-switch into engagement with the spring terminals 25 28 or 29 32.

30 I prefer not to have the reversing-switch close or open the motor-circuit, and in this embodiment I have provided a main switch to accomplish this. As shown in the drawings, 40 is one terminal of the motor-circuit and preferably consists of fixed spring-jaws. The other terminal may be a contact portion 41, adapted to enter between said jaws, and I prefer to mount it on an arm 42, pivoted to the slate at 42^a. As the main switch should 40 be closed by a pull of the shipper-rope in either direction from the position shown in full lines in Fig. 1 and opened by a pull in the opposite direction I have provided a plurality of cams, in the present embodiment 45 formed by pivoted arms 43 44, having cam-faces 45 46, making an angle with each other and having intermeshing segmental gears 47 48, so that when one arm is moved the other will also be moved in the same direction.

50 49 is an operating part consisting of a roller pivoted to a head 50, which is supported on the coiled spring 51. The roller 49 is connected to the shipper-rope by the arm 39 on the rack 18, which carries spring 51.

55 52 is a projection from cam 43 and carries pins 53 54, standing on either side of arm 42 and forming a connection between cam 43 and the arm for moving the same. As rack 18 is moved in one direction or the other from 60 the position shown in full lines in Fig. 1 the rollers 38 and 49 will strike cam-face 45 or 46 and close the reversing-switch and also the main switch. In order to close the reversing-switch first, I have cut away the cam-faces 55 45 and 46 at 45^a 46^a slightly more than in cam 33. As rack 18 is moved to the left from the position shown in full lines in Fig. 1

the reversing-switch will be closed first and then the main switch. As the rack is moved to the right from the dotted position 70 in Fig. 1 the arm 42 will be moved to the left. In order to make a quick break between contact portion 41 and the spring-jaws 40 to avoid arcing, I have provided a spring which automatically exerts its force on arm 75 42 to snap it to the left before the contact portion 41 leaves the terminal 40. In this embodiment 55 is the spring attached to the arm at one end and at the other to the slate at 56— a point beyond the pivot of the arm, Fig. 2. 80 As the arm moves to the left from the dotted position of Fig. 1 it will pass the dead-center of the pull of spring 55 before contact portion 41 leaves jaws 40. Consequently the spring will then snap the arm to the left and 85 make a quick break of the motor-circuit.

In order to hold the arm 13, carrying contact-piece 12, from moving forward over the rheostat while the motor-circuit is open, I 90 preferably use a trigger 57, sliding in a guide-way 58 and connected to the cam 44 by a link 59. The trigger is normally in the position shown in full lines in Fig. 1, below pin 60 on arm 13, but when the main switch is closed the trigger is retracted.

95 It often happens that the motor-circuit is opened by the blowing of a fuse or from other cause, and to prevent the arm 13 moving forward over the rheostat while the circuit is open I have provided a lock therefor which 100 operates as soon as the circuit is broken. In the present embodiment this consists of a solenoid 61, carried on arm 13 and having a core 62, which is provided with, preferably, a plurality of teeth engaging, preferably, a 105 segment 64 of stationary teeth. When the reversing-switch is closed, the circuit through the solenoid is closed and the arm 13 unlocked; but if the motor-circuit is open the lock instantly operates. The arm cannot 110 then be moved to cut out any more resistance until the motor-circuit is again closed.

I am aware that many changes may be made in the constructions herein shown and described without departing from the spirit of 115 my invention, and I therefore do not desire to be limited to the embodiment herein disclosed.

What I claim is—

1. In a motor-controller in combination, a 120 rheostat in the motor-circuit, including a series of terminals and resistances between the same, a switch in said circuit including a pivoted arm carrying a contact-piece adapted to move over said series of terminals to cut out 125 the resistances of said rheostat, a dash-pot to control the speed of movement of said arm, a lock to prevent the forward movement of said switch, and means including a solenoid carried by said arm and having a core adapted 130 to engage a stationary series of teeth, and a connection from the motor-circuit through said solenoid to automatically unlock the same when the motor-circuit is closed.

2. In a motor-controller in combination, a rheostat in the motor-circuit including a series of terminals and resistances between the same, a switch in said circuit including a pivoted arm carrying a contact-piece adapted to move forward over said series of terminals by gravity to cut out the resistances of said rheostat, a dash-pot to control the speed of movement of said arm, a lock to prevent the forward movement of said switch, and means including a solenoid carried by said arm and having a core adapted to engage a stationary series of teeth, and a connection from the motor-circuit through said solenoid to automatically unlock the same when the motor-circuit is closed.

3. In a motor-controller in combination, a rheostat in the motor-circuit, a switch also in said motor-circuit and adapted to automatically move over the same and cut out resistances therein, a lock adapted to hold said switch from passing over said rheostat, a plurality of cams having faces making an angle with each other, an operating part located between said faces and movable in either direction to strike and move one of said cams, and a connection therefrom to said lock to release the same when one of said cams is moved.

4. In a motor-controller in combination, a rheostat in the motor-circuit, a contact-piece in said circuit adapted to pass over the same, a movable rack, a connection from the same including a rotatable wheel meshing with said rack and a link attached thereto and to a movable stop engaging said arm to cause said contact-piece to move over said rheostat and cut out the resistances thereof on a movement of said rack in either direction.

5. In a motor-controller in combination, a rheostat in the motor-circuit, a contact-piece in said circuit adapted to pass over the same and carried by a pivoted arm adapted to fall by gravity when released, a dash-pot to control the speed of movement of said arm, a movable rack, a connection from the same to said pivoted arm to release the same and cause said arm to fall and move said contact-piece over said rheostat to cut out the resistances thereof on a movement of said rack in either direction.

6. In combination, a car, a device for moving the same including a motor, a rheostat in the motor-circuit, a switch adapted to automatically move over said rheostat and cut out resistances thereof, a main switch, a reversing-switch and reversing connections also in said motor-circuit, controlling means extending to said car and connections therefrom to said main and reversing switches adapted to close said reversing-switch and then said main switch, a stop for said rheostat-switch movable independently thereof and adapted to control the position of said rheostat-switch on said rheostat, and a connection between said controlling means and stop for moving the latter.

7. In combination, a car, a device for moving the same including a motor, a rheostat in the motor-circuit, a pivoted arm carrying a switch also in the motor-circuit adapted to fall by gravity and move said switch over said rheostat and cut out resistances thereof, means for retarding the fall of said switch-arm, a main switch, a reversing-switch and reversing connections also in said motor-circuit, controlling means extending to said car and connections therefrom to said main and reversing switches to close said reversing-switch and then said main switch, a stop for said arm movable independently of and away from the same and adapted to control the position of said rheostat-switch on said rheostat, and a connection between said controlling means and stop for moving the latter to the desired position.

8. In combination, a car, a device for moving the same including a motor, a rheostat in the motor-circuit, a switch adapted to automatically move over the same and cut out resistances thereof, a main switch, a reversing-switch and reversing connections also in said motor-circuit, controlling means extending to said car and connections therefrom to said main and reversing switches including a reciprocating rack adapted to close said reversing-switch and then said main switch, a stop for said rheostat-switch movable independently thereof and adapted to control the position of said rheostat-switch on said rheostat, and a connection between said rack and stop for moving the latter on a movement of said rack in either direction.

9. In a motor-controller in combination, a motor, a rheostat in the motor-circuit, a switch adapted to move over the same to cut out the resistances thereof, a reversing-switch also in said motor-circuit, a main switch adapted to open and close said circuit, a reciprocating rack and connections from the same to said three switches to close said reversing-switch and then close said main switch and move said rheostat-switch forward to decrease the resistance of the motor-circuit, on a movement of the rack in either direction.

10. In a motor-controller in combination, a motor, a rheostat in the motor-circuit, a switch adapted to move over the same to cut out the resistances thereof, a reversing-switch also in said motor-circuit, a main switch adapted to open and close said circuit, a reciprocating rack and mechanical connections from the same to said three switches to close said reversing-switch and then close said main switch and move said rheostat-switch forward to decrease the resistance of the motor-circuit on a movement of the rack in either direction.

11. In an elevator mechanism in combination, a car adapted to be raised and lowered in suitable guideways, hoisting means to raise said car including an electric motor, a rheostat including a series of resistances in the

motor-circuit, a switch adapted to move over said rheostat and cut out the resistances thereof thereby decreasing the resistance of said circuit and increasing the speed of the motor, 5 a reversing-switch also in said motor-circuit, a rack adapted to move in either direction, and mechanical connections from the same to said switches to close said reversing-switch and then move said rheostat-switch forward to 10 decrease the resistance of the motor-circuit on a movement of said rack in either direction.

12. In a motor-controller in combination, a rheostat in the motor-circuit, a switch in said circuit adapted to travel over said rheostat and 15 cut out the resistances therein, and means to automatically lock said switch in any position in its traverse when the motor-circuit is opened.

13. In a motor-controller in combination, a rheostat in the motor-circuit, a pivoted switch-arm having a contact-piece in said circuit adapted to travel over said rheostat and cut 20 out the resistances therein, and means including a solenoid carried by said arm, a core for 25 said solenoid and an electrical connection from said motor-circuit through said solenoid whereby said switch is automatically locked in any position in its traverse when the motor-circuit is opened.

30 14. In a motor-controller in combination, a rheostat in the motor-circuit, a pivoted switch-arm having a contact-piece in said circuit adapted to travel over said rheostat and cut 35 out the resistances therein, and means including a solenoid carried by said arm, a core for 40 said solenoid having a tooth adapted to engage a stationary series of teeth and an electrical connection from said motor-circuit through said solenoid whereby said switch is automatically locked in any position in its 45 traverse when the motor-circuit is opened.

15. In a motor-controller in combination, a switch in the motor-circuit including a terminal and a movable contact-piece, means to 45 move said contact-piece to close said switch including a plurality of cams having faces making an angle with each other, an operating part located between said faces and movable in either direction to strike and move one 50 of said cams and a connection between said cams and contact-piece whereby it is moved toward said terminal when either of said cams is moved.

16. In a motor-controller in combination, a 55 switch in the motor-circuit including a terminal and a movable contact-piece, means to move said contact-piece to close said switch including a plurality of pivoted arms having faces making an angle with each other, an operating part located between said faces and 60 movable in either direction to strike and move one of said pivoted arms, and a connection between said pivoted arms and contact-piece whereby it is moved toward said terminal 65 when either of said arms is moved.

17. In a motor-controller in combination, a switch in the motor-circuit including a ter-

70 minal, a movable contact-piece and an arm carrying the same, means to move said arm to close said switch including a plurality of cams having faces making an angle with each other, an operating part located between said faces and movable in either direction to strike and move one of said cams, and a connection between said cams and contact-piece whereby it is moved toward said terminal when either of said cams is moved.

18. In a motor-controller in combination, a switch in the motor-circuit including a terminal and a movable contact-piece, means to 80 move said contact-piece to close and open said switch including a plurality of cams having faces making an angle with each other, an operating part located between said faces and movable in either direction to strike and move 85 one of said cams, and a connection between said cams and contact-piece whereby it is moved toward said terminal when either of said cams is moved, and a spring adapted to snap open said switch before the contact-piece 90 leaves the terminal.

19. In a motor-controller in combination, a switch in the motor-circuit adapted to open and close said circuit and including a terminal, a pivoted arm and a contact-piece carried 95 by said arm and adapted to make electrical connection with said terminal, means to move said arm, to open and close said switch, including a plurality of pivoted arms carrying intermeshing gears and having faces which 100 make an angle with each other, an operating part located between said faces and movable in either direction to strike and move one of said pivoted arms, a connection between said pivoted arms and contact-piece including a 105 projection from one of said pivoted arms which engages said first arm whereby the latter is moved toward said terminal when either of said cams is moved, and a spring adapted to snap said switch open after the 110 contact-piece has been moved a short distance toward the open position.

20. In a motor-controller in combination, a switch in the motor-circuit including a terminal and a movable contact-piece, means to 115 move said contact-piece to close said switch including a plurality of cams having faces making an angle with each other, an operating part located between said faces and movable in either direction to strike and move 120 one of said cams, a connection between said cams and contact-piece whereby it is moved toward said terminal when either of said cams is moved, a reversing-switch also in the motor-circuit, and means to automatically close 125 said reversing-switch before the other switch is closed.

21. In a motor-controller in combination, a switch in the motor-circuit including a terminal and a movable contact-piece, means to 130 move said contact-piece to close said switch including a cam having faces making an angle with each other, an operating part located between said faces and adapted to strike the

same and move said cam and switch in one direction or the other to reverse the motor connection.

22. In a motor-controller in combination, a switch in the motor-circuit including a terminal and a movable contact-piece, means to move said contact-piece to close said switch including a plurality of cams having faces making an angle with each other, an operating part located between said faces and movable in either direction to strike and move one of said cams, a connection between said cams and contact-piece whereby it is moved toward said terminal when either of said cams is moved, a rheostat in the motor-circuit, a contact-piece also in said circuit and adapted to move over said rheostat, and means connecting with the aforesaid operating part and adapted to cause said rheostat and contact-piece to move forward over the same to cut out the resistances thereof after said switch has been closed.

23. In an elevator mechanism in combination, a car, hoisting mechanism for the same including an electric motor, a reversing-switch and connections in said motor-circuit to reverse the direction of rotation of the armature of said motor, a second switch also in

said motor-circuit adapted to open and close said circuit, a rheostat also in said motor-circuit, a pivoted arm carrying a contact-piece and adapted to automatically move over said rheostat to cut out the resistances thereof, a reciprocating rack, a toothed wheel meshing with said rack, a link between said toothed wheel and pivoted arm whereby said contact-piece is caused to move forward over said rheostat on a rotation of said wheel in either direction, a pair of pivoted arms having sloping faces, and a connection between said arms and main switch whereby the same may be closed or opened by a movement of either arm, an operating part located between said faces and reciprocated by said rack to contact with and move said sloping arms, and a connection from said rack to said reversing-switch to close the same before said main switch is closed and on a movement of said rack in either direction.

Signed at New York, N. Y., this 17th day of December, 1900.

RUMSEY W. SCOTT.
